UNITED STATES PATENT OFFICE.

GEORGE B. POST, OF NEW YORK, N. Y.

BOAT.

Application filed October 25, 1926. Serial No. 143,949.

My invention relates to boats and in particular to a boat driven by an air propeller. It is the object of my invention to provide a boat of the free bottom type adapted to draw the minimum of water so as to be able to be operated in extremely shallow waters as well as under deep and rough water conditions.

It is another object of my invention to 10 provide in a marine vessel a combined air and water rudder so arranged that below a predetermined speed the water rudder will control the movements of the boat, and above a predetermined speed the water rudder will be rendered inoperative and the air rudder will become fully operative.

It is a further object to provide such a combination of rudders which will be automatically operated according to the speed of 20 the vessel and the quantity of air passing by the air rudder.

It is a further object to provide a novel 25 form of mounting and protecting the motor and propeller and of locating the power plant with respect to the boat structure and the rudder.

Referring to the drawings:

Figure 1 is a side elevation of the complete 30 installation with the water rudder in lowered position;

Figure 2 is a detail view in elevation of the rudders with the water rudder lowered as it will be when either in operative position or during the period in which the boat 35 is controlled by the water rudder;

Figure 3 is a similar view to Figure 2 showing the water rudder in its elevated and inoperative position when the air rudder is steering the boat;

40 Figure 4 is a plan view of the rudders and the control vanes for the water rudder;

Figure 5 is a perspective of the bottom of the hull of the boat;

45 Figure 6 is a diagrammatic perspective showing the detail nature of the propeller guard so arranged as to protect the passengers but not to interfere with the slip stream from the propeller, while protecting the propeller.

50 Referring to the drawings in detail, a boat hull is provided which may be of any suitable character, preferably of the hydro-plane type, although my invention is not so limited. In the particular embodiment of 55 the hull illustrated in the present application, it will be observed that I provide bot-

tom surfaces 1, which terminate rearwardly in a step 2 and an elevated stern section 3. A keel 4 is provided.

The bottom portions 1 terminate laterally 60 on the chine line 5. The bottom of the boat is substantially flat having imparted to it a slightly concave arcuate section, which becomes of gradually decreasing concavity from bow to step line. 65

When proceeding up to about ten miles an hour, the boat proceeds with most of the hull in the water but at higher speeds the bow lifts and the boat rests upon the rear quarter. It is above this speed of 10 miles 70 an hour that the water rudder lifts, and the slip stream from the propeller is sufficient to give full control by the air rudder.

Mounted upon the hull aft of the midships of the boat is a motor of any suitable 75 type, generally designated 6. It is provided for its support with a pair of diverging, forwardly-disposed engine struts 7, a pair of laterally-disposed, downwardly and rearwardly extending struts 8 and a pair 80 of downwardly-extending, transversely-disposed struts 9. It is braced laterally with crossed wires in the plane of the struts 7 and 8. The struts 7 do not extend to the gunwale of the boat. The lower ends of the 85 struts 9 and 8 extend to the deck inside the gunwale, the lower ends of such struts 8 and 9 terminating at a common point on the after deck.

This arrangement gives a diagonally-braced, four-point foundation for the engine, sufficiently elevated above the boat deck to provide for the free revolution of the propeller 10 within its cage. This cage or guard consists of transverse ovoid sections 90 of netting, designated 11, placed between the propeller and the bow of the boat. These sections are provided with transverse braces 95 12. An interconnecting section below the motor, designated 13, is provided.

On either margin of the ovoid, transverse guard sections, are semi-circular sections for guarding the ends of the propeller, designated 14, provided with suitable braces 15. The deck 16 of the boat is lowered below 105 the gunwales 17 in order to quickly carry away any accumulation of water from the spray by holes 17^a and to protect the propeller.

The sides of the boat adjacent the propeller may be protected by canvas guards 18 to prevent any water from coming in con-

tact with the propeller through the operation of the boat.

Turning to the next feature of this invention, the rudders, it will be observed that 5 I provide on the stern of the boat a vertical rudder post 19 suitably braced by the diagonal braces 20. Pivoted on this rudder post is an air rudder 21. Pivots connected to the post and to the air rudder is a 10 water rudder 22.

A tiller yoke 23 operated by the tiller ropes 24 is provided for the purpose of moving the air and water rudders, as a unit on the rudder post 19.

15 Connected to the tiller ropes 24 is the usual steering wheel 25. Any form of control of these rudders may be provided as well known in marine practice.

The water rudder 22 has pivotally connected thereto at 26 a link 27 which extends upwardly within the air rudder projecting out at the top thereof where it is pivotally connected at 28 to an arm 29 pivoted at 30 to a bracket 31 on top of the rudder post 19.

25 This arm 29 is rigidly connected to a pair of arms disposed at an angle thereto designated 32 on the ends of which are mounted vanes 33 which are disposed at an angle to the line of movement of the boat. It will be 30 apparent that, when the boat first starts to operate, it will move forwardly under the control of the water rudder but when the slip stream becomes of sufficient force from the air propeller the vanes 33 will be lifted

35 from their position shown in Figure 2 to that position shown in Figure 3. The water rudder will be thereby lifted from the water and the boat will be steered by the air rudder. Therefore, when the speed becomes 40 great, as this boat is capable of from thirty to forty miles an hour, in the particular embodiment illustrated herein, the boat will not be impeded in its speed by a water rudder nor will its draft be increased by the

45 water rudder. Consequently, in a boat of twenty three feet six inches long with a beam of seven feet three inches the draft will be nine inches when at rest but only three to four inches when planing at a speed of 50 about ten miles an hour. When using a ninety horse power motor, I find that the water rudder will be elevated and the boat will be satisfactorily, completely steered by the air rudder.

55 It will be understood that I desire to comprehend within my invention such modifications as may be necessary to adapt it to varying conditions and uses.

Having thus fully described my invention, 60 what I claim as new and desire to secure by Letters Patent, is:—

1. In combination in a boat, for steering a boat, an air rudder, a water rudder, and means automatically operated to render the 65 water rudder inoperative.

2. In combination in a boat, an air rudder, a water rudder, means for moving said rudders for steering purposes as a unit, and air controlled means for rendering said water rudder inoperative when a predetermined 70 amount of air passes by said rudders.

3. In combination in a boat of a rudder post, air and water rudders mounted thereon, means to move said rudders thereon, vane means adapted to be operated upon by the air 75 connected to said water rudder adapted to move the water rudder out of the water upon a predetermined amount of air engaging with said vane means.

4. In combination in a boat, a supporting 80 rudder post, air and water rudders mounted thereon adapted to turn thereon as a unit, means to control said rudders, a link connected to said water rudder, a lever system supported on said rudder post turning with said 85 rudders, vanes carried by said lever system, said lever system being connected to said link whereby the passage of air will elevate said vanes and lift said water rudder.

5. In a boat, a common supporting means, 90 an air rudder and a water rudder pivoted on said means one above the other, said water rudder being adapted to move relative to said air rudder, a link passing through said 95 air rudder connected to said water rudder, vanes connected to said link on either side of said air rudder adapted when elevated by the air to lift said water rudder.

6. In a boat, a common supporting means, 100 an air rudder and a water rudder pivoted on said means one above the other, said water rudder being adapted to move relative to said air rudder, a link passing through said air rudder connected to said water rudder, vanes 105 connected to said link on either side of said air rudder adapted when elevated by the air to lift said water rudder, said connecting means for said vanes consisting of a yoke.

7. In a boat, an air propeller, an air rudder, a water rudder, and means for rendering 110 said water rudder inoperative upon a predetermined air blast from the propeller being achieved.

8. In a boat, an air propeller, an air rudder, a water rudder, and means for rendering 115 said water rudder inoperative upon a predetermined air blast from the propeller being achieved, and a common steering means for said rudders.

9. In a boat, a boat body, a power plant 120 and air propeller mounted thereon, an air rudder mounted in the slipstream from said propeller, a water rudder, vanes mounted in said slipstream connected to said water rudder whereby upon the achievement of a predetermined speed, said vanes will move to render said water rudder inoperative and steering means for said rudders.

10. In a boat, a boat body, a power plant 125 above said body aft of the midships of the 130

- boat, a propeller connected to said power plant, a rudder post on the stern of said boat, a relatively large air rudder mounted thereon in the slipstream from the propeller, 5 a relatively small water rudder mounted therebeneath, air vanes connected to said water rudder mounted on said rudder posts adapted to elevate the water rudder when a sufficient blast from the propeller is delivered 10 against them, and a common steering means for said rudders.
11. In a boat, a boat body, a power plant above said body aft of the midships of the boat, a propeller connected to said power 15 plant, a rudder post on the stern of said boat, a relatively large air rudder mounted thereon in the slipstream from the propeller, a relatively small water rudder mounted therebeneath, air vanes connected to said water rudder mounted on said rudder posts adapted to elevate the water rudder when a sufficient 20 blast from the propeller is delivered against them, and a common steering means for said rudders, and a guard for said propeller.
- 25 12. In a boat, a boat body, a power plant above said body aft of the midships of the
- boat, a propeller connected to said power plant, a rudder post on the stern of said boat, a relatively large air rudder mounted thereon in the slipstream from the propeller, a relatively small water rudder mounted therebeneath, air vanes connected to said water rudder mounted on said rudder posts adapted to elevate the water rudder when a sufficient 30 blast from the propeller is delivered against them, and a common steering means for said rudders, and a guard for said propeller, 35 said guard being arranged forwardly and laterally of said propeller in such a manner as not to interfere with the slipstream therefrom.
13. In combination, a hydroplane boat body, an air rudder, a water rudder, steering means therefor, air controlled means for rendering said water rudder inoperative upon a predetermined speed being achieved by said boat, a power plant and an air propeller so arranged as to deliver its slipstream to said air rudder, and means for controlling the water rudder. 40 45 50

In testimony whereof I affix my signature.
GEORGE B. POST.
